UNITED STATES PATENT OFFICE.

EMIL TYDEN, OF HASTINGS, MICHIGAN.

DESIGN FOR A SEAL-BODY.

SPECIFICATION forming part of Design No. 29,387, dated September 20, 1898.

Application filed August 10, 1898. Serial No. 688,305. Term of patent 14 years.

To all whom it may concern:

Be it known that I, EMIL TYDEN, a citizen of the United States, residing at Hastings, county of Barry, and State of Michigan, have 5 invented and produced a new and original Design for a Seal-Body, which is fully set forth in the following specification, reference being had to the accompanying drawings, forming a part thereof.

10 My invention relates to a design for bodies for self-locking seals, and it is illustrated in the accompanying drawings, in which—

Figure 1 is an edge elevation of a seal-body embodying my design, and Fig. 2 is a side 15 elevation of the same.

The general form of this seal-body is bulbous or quasi-spherical. It is substantially circular about an axis A and has a narrow and

thin peripheral bead or distinctly-marked rib A' in a plane at right angles to said axis. 20

The essential features of my design are the bulbous or quasi-spherical seal-body, circular about a certain axis, having a peripheral bead or distinctly-marked rib in a plane at right angles to the axis. 25

I claim—

The design for a seal-body herein shown and described.

In testimony whereof I hereunto set my hand, at Chicago, Illinois, this 5th day of August, 1898.

EMIL TYDEN.

In presence of—

W. D. HAYES,
J. T. LOMBARD.
